William Ernest Harwell, 311 Touraine Road,
Grosse Pointe Farms, Mich.

Filed Aug. 30, 1962, Ser. No. 71,506

Term of patent 14 years

(Cl. D44—29)

FIG. 2

FIG. 3

FIG. 1 is a top plan view of a combined can punch and bottle opener, showing my new design;

FIG. 2 is a side elevational view thereof; and

FIG. 3 is a side elevational view opposite to that in FIG. 2.

The bottom of the opener is substantially plain and unornamented.

I claim:

The ornamental design for a combined can punch and bottle opener, substantially as shown and described.
